UNITED STATES PATENT OFFICE.

TIMOTHY JOSEPH BURRELL, OF EL PASO, TEXAS.

TRACK-SANDING DEVICE.

1,426,627.

Specification of Letters Patent. Patented Aug. 22, 1922.

Application filed June 16, 1921. Serial No. 478,080.

To all whom it may concern:

Be it known that I, TIMOTHY JOSEPH BURRELL, a citizen of the United States, residing at El Paso, in the county of El Paso 5 and State of Texas, have invented certain new and useful Improvements in Track-Sanding Devices; and I do declare the following to be a full, clear, and exact description of the invention, such as will enable 10 others skilled in the art to which it appertains, to make and use the same.

This invention relates broadly to an improved track sanding device, having more 15 particular reference to an improved nozzle for the fluid pipe of such device.

The object of the invention is to provide 20 an improved nozzle of simplified construction which embodies novel spring means which functions as a valve and serves to close one of the ends of the bore of the nozzle when the air is shut off to prevent sand and grit from accumulating in and clogging the bore as now happens with the types of nozzles in use at this time.

25 Other objects and advantages of the invention will be apparent during the course of the following description.

In the accompanying drawings forming a 30 part of this specification in which like numerals are employed to designate like parts throughout the same:

35 Figure 1 is a sectional view, with parts in elevation, of a conventional type of sanding device equipped with a nozzle constructed in accordance with this invention.

Figure 2 is a central vertical enlarged sectional view through the nozzle.

Figure 3 is a top plan view thereof.

To enable the reader to obtain a clear understanding of my nozzle, I have shown it 40 associated with a conventional type of sanding device which comprises an irregular conduit A which is bolted or otherwise secured to the dome B from which the sand is supplied. The intermediate portion of the conduit is inclined as shown to cause the sand to fall, by gravity, into the lowermost dished portion of the conduit to overcome, as is 45 obvious, accidental falling of the sand onto the track caused by the vibration of the car.

The outer end of the conduit is downturned as indicated at C and this end has a depending pipe D connected therewith, it being 50 obvious that this pipe extends down and into 55 close proximity with the track to drop sand onto the latter. It may also be pointed out,

that, as is usual, the conduit is formed on one side with a covered hand-hole E which serves to permit free access to be had to the interior of the conduit. The dished portion 60 of the latter is formed with an opening with which an air pipe F communicates. Under ordinary circumstances, a bored bushing is fitted into the opening in the conduit and communicates with the pipe F to supply a 65 jet of air to the conduit to force the sand from the latter and onto the track through the depending pipe D. As before indicated, this invention contemplates substituting for the old type of nozzle, which becomes 70 frequently clogged with sand, the new type of nozzle shown. It is hardly necessary to say here, that the parts of the device so far described constitute no part of this invention and are in use at this time. 75

The invention, as above stated, resides in the employment of a novel nozzle 1, the same having longitudinal bore extending entirely therethrough to permit passage of a restricted quantity of air or other fluid. The 80 bore 2 is reduced in diameter intermediate its ends as indicated at 3. Further examination of the nozzle will disclose the fact that it is screw-threaded at one end as indicated at 4, and is provided intermediate its ends 85 with a flange 5 and has upper conical or pointed end 6. A pair of oppositely disposed spring fingers 7 are secured at their lower ends to the flange 5, having their upper ends bent inwardly and toward each 90 other as indicated at 8 and increased somewhat in width. The inherent resiliency of these fingers automatically forces their free ends together in such a way as to normally cover the upper end of the bore 2 so that it 95 is practically impossible for sand to enter this bore and clog it in such a way as to prevent free passage of air therethrough.

It is obvious that although the extremities of the fingers come together in such a way 100 as to close the upper passage of the nozzle, they are sufficiently resilient to be sprung apart as indicated in Fig. 2 when the air pressure is supplied to the nozzle.

In operation, sand is fed from the dome B 105 into the conduit A and is caught by the incoming current of air passing through the pipe F and nozzle 1, and carried upwardly and then down from the conduit through the depending pipe D and onto the track or 110 other desired place of deposit. As soon as the air current is shut off, the free ends of

the fingers 7, which were previously spaced apart to permit passage of air through the nozzle, automatically spring together and assume the position disclosed in Fig. 3, thereby closing the passage of the nozzle and preventing the entrance of sand or grit into this passage.

A careful consideration of the description taken in connection with the drawings will 10 be found sufficient, it is thought, to enable persons skilled in the art to which the invention relates to obtain a clear understanding of the same. In view of this, a more 15 lengthy and detailed description will be omitted.

Since probably the best results may be obtained with the construction and arrangement herein shown and described, this is 20 taken as a preferred embodiment of the invention. However, slight minor changes coming within the scope of the subjoined 25 claims may be resorted to.

I claim:

1. A fluid nozzle for disposition in the 25 conduit of a track sanding device comprising a longitudinally bored body, and an exteriorly disposed valve normally closing the upper end of said bore to prevent the entrance of sand, said valve being opened by 30 the pressure of the fluid exerted against it.

2. A nozzle comprising a longitudinally bored body, and a spring finger carried by the body and closing one end of said bore,

being rendered ineffective by the pressure exerted against it.

3. A nozzle of the class described comprising a body having a longitudinal passage extending therethrough, and spaced oppositely disposed spring fingers carried by the body and having free ends arranged to close 40 the upper end of said passage.

4. A nozzle of the class described comprising a longitudinally bored body having a substantially pointed upper end, a screw-threaded lower end and formed intermediate 45 its ends with a flange, and a pair of spring fingers having their lower ends secured to said flange at opposite points, the free ends of said fingers being directed toward each other and their extremities normally contact- 50 ing one another to cover the upper end of said bore.

5. A fluid nozzle for arrangement in the conduit of a track sanding device comprising a longitudinally bored body having a 55 wedge-shaped upper end, and oppositely disposed spring fingers associated with said body and having their upper ends directed toward each other in a manner to cover the upper end of said bore, and said inwardly 60 directed ends being flattened for contact with the flattened faces of said upper end of the body.

In testimony whereof I have hereunto set my hand.

TIMOTHY JOSEPH BURRELL.
